SHOE HEEL

Filed July 9, 1928

INVENTOR
John F. McNamara
By George E. Mueller Atty.

UNITED STATES PATENT OFFICE

JOHN F. McNAMARA, OF CHICAGO, ILLINOIS

SHOE HEEL

Application filed July 9, 1928. Serial No. 291,154.

My invention relates to detachable heels, and has for its main object the provision of a shoe heel which may readily be attached to or removed from the shoe.

5 Another object is the provision of a heel which when partly worn may be changed from one shoe to the other.

Another object is the provision of a detachable heel of simple and economical design, which may be applied to the shoes easily and without the use of any special tools.

Another object is the provision of a detachable shoe heel which may be applied to the shoes without the use of any loose elements such as screws, pins, nails or the like.

Other objects or features of my invention will be apparent from a consideration of the detailed description taken with the accompanying drawings wherein

20 Fig. 1 is a fragmentary view of a man's shoe with a rubber heel of my invention affixed thereto;

Fig. 2 is a bottom view of the same shoe with part of the detachable heel broken away to show the construction thereof;

Fig. 3 is a sectional view taken along lines 3—3 of Fig. 1, and

Fig. 4 is a similar view showing a modified form.

30 The heel of my invention is particularly adapted to be made of rubber, but it may be formed with good results of leather or other suitable compositions, and while the drawing shows a type of shoe particularly adaptable for men's wear I may employ a heel of this design with either women's or children's shoes. The design is particularly adapted, however, for use on men's shoes while a form of heel particularly adapted for women's wear is shown in my co-pending application, Serial Number 291,153, filed July 9, 1928.

The heel is adapted to be applied to a shoe 10 and the heel itself comprises essentially two parts namely a metal portion A which is permanently secured to the shoe and a removable portion B preferably of rubber. The metal portion A which I term a heel holder is made of metal and is so designed that the heel B may be slipped into position and out of position on the shoe very quickly.

Referring now to the heel holder B this comprises a horseshoe portion 11 secured to the heel of the shoe by screws 12, or nails and a downwardly projecting portion 13 which is integral with the horseshoe portion 11. This portion 11 may be of any shape consistent with the results desired, but I prefer the shape shown in the drawings because substantially the same strength is obtained as if a solid frame piece were used, and a great saving in weight is obtained. At the front end of the downwardly projecting or heel holding portion 13 a longitudinal slot 14 is provided, and the front ends of the portion 13 are formed in a scroll 16 as shown in Fig. 2. This metal portion is formed of a spring material and the slot 14 permits the front ends to be forced outwardly as shown in the dotted portion in Fig. 2 so that the rubber heel can be slid into position.

In order to hold the heel more firmly in position, I provide a number of points 17 which are adapted to extend into the periphery of the heel when it is placed in position to form a better grip than is obtained by the spring action of the holder unassisted. While these points may be formed in any way I find it simple to strike them from the material of the heel holder as shown at 17^a in Fig. 1.

The heel B which I employ with the heel holder shown in Figs. 1 to 3 may be a standard type of heel such as the present rubber heel which is purchased in all of the shoe stores and applied to the shoe by nailing, but for actual use I prefer a heel somewhat thicker than the present standard rubber heel or heel cap, but which is in all other respects similar thereto. This permits more of the heel to project below the heel holder in every respect producing a substantially better result.

In Fig. 4 I show a modification wherein the portion 13 is provided with a bead 13^a at the bottom thereof, this bead being formed by bending the material back on itself in the manner shown. With this form the detachable heel is provided with a groove 18 extending entirely around the same so that the bead engages in the groove and holds the heel

firmly in position. In all other respects this form is the same as shown in the main figures, the bead 13^a taking the place of the points 17.

While I have described certain details of my invention to enable those skilled in the art to practice the same the invention is not necessarily restricted to these details, but is defined within the scope of the appended claims.

What I claim as new and desire to protect by Letters Patent of the United States is:

1. A detachable heel construction comprising, a heel holder attached to the heel portion of the shoe and having a resilient downwardly extending member on the outside portion of the shoe heel with longitudinal slits near the front thereof permitting the front projecting ends of the resilient member to be extended slightly away from the shoe, and a removable heel pad insertable into said holder and held against forward movement by said resilient projecting ends.

15 2. A detachable heel construction comprising, a heel holder attached to the heel portion of the shoe and having a resilient downwardly extending member on the outside portion of the shoe heel with longitudinal slits near the front thereof permitting the front projecting ends of the resilient member to be extended slightly away from the shoe, a removable heel pad insertable into said holder, and means on said resilient member and cooperating with the heel pad for positively preventing the pad from slipping downwardly out of engagement with the resilient member.

20 3. A detachable heel construction comprising, a heel holder including a base in horseshoe form secured to the shoe heel portion with a tie member across the horseshoe ends, and a resilient member projecting downwardly from the horseshoe shaped base and having longitudinal slits at the front ends thereof near the base, forming two outwardly extendable front end portions, and a heel pad extending between the extendable front end portions and engaged and held by said resilient member, and means on the resilient member and cooperating with the heel pad for positively preventing downward slipping movement of said heel pad.

25 4. A detachable heel construction comprising, a heel holder including a base in horseshoe form secured to the shoe heel portion with a tie member across the horseshoe ends, and a resilient member projecting downwardly from the horseshoe shaped base and having longitudinal slits at the front ends thereof near the base, forming two outwardly extendable front end portions, a bead at the lower inside edge of said resilient member and extending entirely around the same, and a heel pad with an outside groove engaging said bead and held against frontward movement by the engagement of said extendable front end portions.

5. In a detachable shoe heel, a heel holder including a base secured to the shoe heel portion and a resilient member projecting downwardly therefrom having longitudinal slits at the front end thereof near the base, forming two outwardly extendable front end portions, a bead at the lower inside edge of said resilient member, and a heel pad with a groove adapted to receive said bead for preventing downward displacement of the pad with respect to the holder.

In witness whereof, I hereunto subscribe my name this 19th day of June, 1928.

JOHN F. McNAMARA.
